UNITED STATES PATENT OFFICE.

CHARLES A. SUTTON, OF PITKIN, COLORADO.

DESIGN FOR A SLIDE FOR TONGS-HANDLES.

SPECIFICATION forming part of Design No. 32,223, dated February 13, 1900.

Application filed January 13, 1900. Serial No. 1,395. Term of patent 7 years.

To all whom it may concern:

Be it known that I, CHARLES A. SUTTON, a citizen of the United States, residing at Pitkin, in the county of Gunnison and State of Colorado, have invented a new and original Design for a Slide for Tongs-Handles, of which the following is a specification, reference being had to the accompanying drawing, forming a part thereof.

In the drawing I have shown a perspective view of my invention; and, as seen, the leading or material feature of my design consists of a flat body *a*, substantially round and having its periphery corrugated, making its boundary-line a series of arcs *b*. At the center of the body *a* is a slot *c*, having parallel sides connected at their ends by arcs, and

distributed through the entire body are a number of circular perforations *d*, arranged as shown.

It is also apparent that this design is applicable to slides for other than the handles of tongs, such as pincers, pliers, &c.

Having thus described my invention, what I claim as new, and desire to secure by Letters Patent, is—

The design for a slide for tongs-handles as herein shown and described.

In testimony whereof I sign my name in the presence of two subscribing witnesses.

CHARLES A. SUTTON.
